UNITED STATES PATENT OFFICE

CHARLES N. PROUTY, OF SPENCER, MASSACHUSETTS

INNER SOLE

Application filed June 13, 1928. Serial No. 285,144.

This invention relates to an innersole for a welted shoe.

The principal objects of the invention are to provide a construction of innersole which 5 will permit of the use of a piece of leather for the sole of very much less thickness than is ordinarily used, and secure the necessary strength and rigidity by a means considerably less expensive than the leather, and at 10 the same time retain all the wearing qualities of the grade of leather used; also to provide a combination of leather innersole, canvas lining, and reinforcement of such arrangement that the sole will be just as good as if 15 made of a piece of leather of the same grade and of practically twice the thickness.

Other objects and advantages of the invention will appear hereinafter.

Reference is to be had to the accompanying 20 drawings, in which

Fig. 1 is a plan of a complete innersole constructed in accordance with this invention;

Fig. 2 is an enlarged sectional view on the line 2—2 of Fig. 1, and

25 Fig. 3 is a plan view of the reinforcing member.

In accordance with this invention, I make the leather innersole 10 of a high grade of leather but of only about half the thickness 30 of the innersole as usually constructed. It is channeled at 11 in the usual way to provide the usual channel flap 13 and is provided on its upper side with a reinforcement 12 consisting of a piece of paper board of strong 35 character.

This reinforcement is cut out around its periphery so as to be spaced from the channel and not project into it and not come close at 40 any point to the up-turned channel flap 13 which is turned up when the channel is formed. This reinforcement is cemented or otherwise secured to the upper surface of the sole of the shoe and spaced from the flap as stated. Over these parts is placed the usual 45 canvas facing or inner-lining. It is extended clear to the flap and is cemented to the reinforcement, and also is turned up all around its edge and cemented to the flap or gummed. It 50 constitutes a part of the upturned leather portion and the stitches for securing the upper

are brought through clear down to the upper surface of the innersole. This is possible on account of the fact that the reinforcement does not extend out in position to interfere with these stitches. They are formed close 55 to the surface of the innersole as is the case with a sole made entirely of leather. When sewed, these stitches stretch the canvas over the reinforcement to form a smooth surface thereover.

In wear, it is found that this reinforcement, being formed of a heavy grade of paper or paste-board, is comparatively rigid, and being secured to the innersole and to the canvas will retain its rigidity through a long period 60 of wear, thus causing the sole to wear like a full leather sole and reducing the expense of manufacture materially. There is nothing about the sole to show that it is provided with such a reinforcement and even after long wear 65 this fact does not appear. The insole does not deteriorate any more rapidly than an ordinary sole of the same quality of leather of practically twice the thickness. The upper is sewed to it at the same point as usual 70 and the shoe is of a high quality as far as the 75 sole is concerned.

Although I have illustrated and described only one form of the invention I am aware of the fact that modifications can be made there- 80 in by any person skilled in the art without departing from the scope of the invention as expressed in the claims.

Therefore, I do not wish to be limited to the exact form shown, but what I do claim 85 is:—

1. As an article of manufacture, a welt innersole comprising a leather portion of a com- 90 paratively thin structure and having the usual cut channel around the edge and provided with a reinforcing layer of paper material 95 secured to the innersole and spaced around its edges from the channeled portion thereof throughout its periphery to provide a space entirely around it for sewing the upper to the innersole and receiving the stitches at the level of the bottom of said reinforcing layer.

2. As an article of manufacture, an inner- 100 sole comprising a thin leather portion having a channel around the edge and provided with

- a reinforcing layer of paper material secured to the surface of the innersole and spaced from the channel throughout its periphery to provide a space for sewing the upper to the innersole and receiving the stitches at the level of the top of the innersole, and a layer of canvas over the entire inner portion of the innersole cemented to the reinforcement and to the inside of the channel flap throughout the periphery thereof.
- 5

- 10 In testimony whereof I have hereunto affixed my signature.

CHARLES N. PROUTY.
